UNITED STATES PATENT OFFICE.

GEORGE WESTINGHOUSE, OF PITTSBURG, PENNSYLVANIA; ASSIGNOR TO THE WESTINGHOUSE MACHINE COMPANY, A CORPORATION OF PENNSYLVANIA.

ELASTIC-FLUID TURBINE.

No. 866,171.

Specification of Letters Patent.

Patented Sept. 17, 1907.

Application filed March 28, 1905. Serial No. 252,480.

To all whom it may concern:

Be it known that I, GEORGE WESTINGHOUSE, a citizen of the United States, and a resident of Pittsburgh, in the county of Allegheny and State of Pennsylvania, have invented a new and useful Improvement in Elastic-Fluid Turbines, of which the following is a specification.

This invention relates to elastic fluid turbines.

In turbines in which it is necessary to limit the amount of radial clearances between the rotor and stator elements, considerable difficulty has been encountered in maintaining the necessary clearance while the turbine is operating. The exterior casings or stationary portions of the turbines are liable to and do distort. Because of the high rotational speed to which the rotors are subjected, means are provided at the shaft bearings for allowing them—the said rotors—to rotate about their gravity axes, which may not exactly coincide with their geometric axes. For these reasons and because of certain vibrations to which the shafts may be subjected, the blades carried by the rotors are liable to strike against the stationary parts and be broken off or stripped from their mounting members. The same difficulty will be encountered if the stator vanes are struck by the rotors.

An object of this invention is to produce means for minimizing the harmful effects resulting from the above difficulties; and, further, for so mounting the blades and vanes that if contact does take place between their outer ends and the surfaces adjacent thereto, that the said contact will be a yielding contact.

In the drawings accompanying this application and forming a part thereof, Figure 1 is a fragmentary view in elevation of a row of turbine blades and co-operating vanes embodying this invention; Fig. 2 is a fragmentary view illustrating a now common method of mounting the blades and vanes on their respective holding members; Fig. 3 is a diagram essential in the further description of the invention.

In Fig. 2, the blades 4, which are radially mounted on the rotor 5 by any suitable method, are tied together at their outer ends by a binding strip 6. Between the outer ends of the blades 4 and the stator element clearance 8 is provided, which under all normal conditions is considered sufficient. The stationary vanes 9 are radially mounted to the stator 7 and a similar clearance is provided.

In Fig. 1, the blades are mounted to the rotor and inclined rearwardly from a radial position, or in a direction opposite to that of rotation of the rotor, which is shown by the arrow. The ends of the blades are in this case also tied together by a binding strip 6 and between the ends of the blades and the stator 7 sufficient clearance 8 is provided for normal conditions. The

stationary vanes 9 are mounted to the stator in an inclined position corresponding to the inclination of the rotor blades, and between the ends of the vanes 9 and the rotor, sufficient clearance 10 is provided.

The difficulty encountered by the radial method of mounting the blades is diagrammatically illustrated in Fig. 3, together with a diagrammatic illustration of the means utilized in overcoming the difficulty. The rotor 5, in Fig. 3, is provided with a diagrammatic illustration of a radially mounted blade shown by the dotted lines 11—12, 12—13, and 13—14. The end of the dotted blade is shown in contact with the face of the stator 7. The figure also diagrammatically illustrates a method of inclined blade mounting, shown by the full lines 11—18, 18—19 and 19—14; which, for the sake of comparison is mounted to the rotor 5 at the same point as the radial or dotted blade. With the end of the radial blade in the position shown, and with the rotor revolving in the direction of the arrow, the point 12 of the blade will move to some position, relative to the rotor, to the rear of the one it now occupies, and the blade will be distorted or bent. In moving to the new position, the entire blade is bent and the point 12 will tend to move in the arc 12—15—13 of a circle whose center is at some point 16 in the neutral axis of the blade.

It is evident from the diagram that the point 12 of the radial blade will have to move to the position of the point 13 before it can clear, or before it is yieldingly held against the stator, and as the blade cannot travel through the arc of the circle illustrated it will be broken or stripped from its mounting member. The action of the inclined blade in overcoming this difficulty is diagrammatically shown by the full line blade in Fig. 3. As in the case of the radial blade, it is also shown in contact with the face of the stator, but it is so positioned that the point 18, corresponding to the point 12 of the radial blade, is back of point 16 with reference to the motion of the rotor.

As the point 16 is the center of the arc through which the point 18 will tend to move during the bending of the blade, it is evident that the blade will readily yield to the external pressure of the stator, as the arc 18—22 through which the point 18 will move does not cut the line 17.

The action of the blades illustrated is, of course, exaggerated for the sake of description, but will aptly apply to the stator and to the inclined method of mounting the vanes.

In Fig. 2 the edge 20 of the blades or vanes corresponds with the point 12 in the exaggerated blade of Fig. 3, and the edge 21 of the blades and vanes in Fig. 1 corresponds with the point 18.

The tendency of the inclined blades to straighten out

under the influence of the centrifugal force and to occupy radial positions is overcome by the action of the binding strip 6 to which the ends of the blades are rigidly mounted, as a change in the relative position of the blades would tend to distort the portion of the binding strip between the separate blades.

Having thus described my invention, what I claim as new and useful and desire to secure by Letters Patent is:

- 0 1. In an elastic fluid turbine, rotor blades mounted so as to incline rearwardly from radial lines and stator vanes inclining forwardly from radial lines in relation to the direction of rotation of the rotor, and means for tying the outer ends of a plurality of said blades together.
- 5 2. In combination in an elastic fluid turbine, a rotor provided with annular rows of moving blades so mounted as to incline rearwardly from radial lines and a stator element provided with annular rows of stationary vanes so mounted as to incline forwardly from radial lines in relation to the direction of rotation of the rotor and means for tying the outer ends of a plurality of said blades together.
- 10 3. In combination in an elastic fluid turbine, a rotor element provided with annular rows of rearwardly-inclined rotating blades extending in close proximity with the turbine casing and a stator element provided with annular

rows of forwardly-inclined stationary vanes interleaving with said rows of moving blades.

4. In combination in an elastic fluid turbine, a plurality of annular rows of rearwardly-inclined moving blades and alternate rows of forwardly-inclined stationary vanes.

30

5. In combination in an elastic fluid turbine, a stator element provided with an annular row of inclined stationary blades and means for tying the outer or free ends of said blades together.

35

6. In combination in an elastic fluid turbine, a stator element provided with an annular row of forwardly inclined stationary blades and means for tying the outer or free ends of said blades together.

40

7. In combination in an elastic fluid turbine, a stator element provided with two or more annular rows of inclined stationary blades and means for tying the outer or free ends of the blades of each row together.

45

8. In combination in an elastic fluid turbine, a stator element provided with two or more annular rows of forwardly inclined stationary blades and means for tying the outer or free ends of the blades of each row together.

In testimony whereof, I have hereunto subscribed my name this seventeenth day of March, 1905.

GEO. WESTINGHOUSE.
